CHALK HOLDER

Harriet Myrtle Solheim, Parker, S. Dak.

Application October 22, 1937, Serial No. 170,499

1 Claim. (Cl. 120—13)

This invention appertains to new and useful improvements in school appliances and more particularly to a holder especially adapted for holding chalk.

As is well-known, the use of chalk in writing or illustrating on blackboards is quite disagreeable as powdered chalk is left on the hands and small particles fall onto the floor and become pulverized thereon. Moreover, small children, after writing with chalk attempt to clean their hands by wiping them on their clothing, thus soiling their clothes. Furthermore, the holding of chalk is to many people offensive in cases where the skin of their fingers is sensitive.

The principal object of the present invention is to provide a holder for chalk which will eliminate the necessity of actual contact of the chalk with the hands.

Another important object of the invention is to provide a chalk holder wherein chalk can be used until it is practically exhausted.

These and various other important objects and advantages of the invention will become apparent to the reader of the following specification.

In the drawings:

Figure 1 represents a side elevational view of the chalk holder showing a piece of chalk protruding from one end thereof.

Figure 2 represents a longitudinal sectional view through the chalk holder with a stick of chalk therein.

Figure 3 is a cross sectional view taken substantially on line 3—3 of Figure 1.

Figure 4 is a side elevational view of the spirally slotted tube.

Figure 5 is a side elevational view of the rotatable tube.

Figure 6 is a side elevational view of the chalk holding clip and slider unit.

Referring to the drawings wherein like numerals designate like parts, it can be seen that numeral 5 represents an elongated cylindrical shell having the small opening 6 at one end thereof to rotatably receive the neck portion 7 which connects the knob 8 to the head 9 of the elongated rotatable tube 10. This tube 10 is provided with the longitudinally extending slot 11 through which the stud 12 extends, this stud 12 also extending through the longitudinally extending spiral slot 13 of the sleeve 14. This sleeve 14 is interposed between the tube 10 and the shell 5 and is provided with a longitudinally extending spirally arranged rib 15 which serves to space the main portion of the sleeve 14 from the shell by a slit so as to leave the space 16 in which the head 17 of the stud 12 can travel.

One end of the sleeve 14 abuts the inturned end

portion 18 of the shell 5 through which end the chalk stick 19 projects while the opposite end of the sleeve 14 is provided with the outwardly disposed circumferential flange head 20 which bears against the inside of the shell 5 at the knob 5 end of the shell 5.

The slide block 21 inside of the tube 10 and from which the stud 12 protrudes is provided with the spring finger 22 for gripping the inner end 10 of the chalk stick 19 as clearly shown in Figure 2.

Obviously, by rotating the knob 8, the tube 10 is rotated and as the stud 12 rides in the slot 13 of the sleeve 14, the chalk gripping block 21 will move longitudinally in the shell 5, feeding the chalk outwardly to the extent needed.

While the foregoing specification sets forth the invention in specific terms, it is to be understood that numerous changes in the shape, size and material may be resorted to without departing from the spirit and scope of the invention as claimed hereinafter.

Having described the invention what is claimed as new is:

A chalk holder comprising an elongated shell 25 having one end rounded and provided with a centrally arranged opening through which the chalk passes, the opposite end being flat and provided with a centrally arranged opening, an elongated tubular member fitting in the shell and having one 30 end bearing against the flat end thereof and its opposite end against a portion of the rounded end, said tubular member having a spiral slot therein, a spiral rib on the exterior circumference of the tubular member, said rib engaging the inner circumference of the shell to space the tubular member from the shell, a second elongated tubular member fitting in the first tubular member 35 with its ends engaging the flat and rounded ends of the shell, that end of the second tubular member which engages the flat end of the shell being closed, a stem projecting from said closed end and passing through the opening in the flat end of the shell, a knob connected with the outer end of the stem, said second tubular member having a longitudinal extending slot therein extending 40 from a point spaced from the closed end of the second tubular member through the other end, a block fitting in the second tubular member, a headed stem connected with a side portion of the block and passing through the slot of the second tubular member and through the spiral slot of the first tubular member with its head located in the space between the shell and the first tubular member, and spring fingers carried 45 by the block for gripping a piece of chalk placed 50 in the device.

HARRIET MYRTLE SOLHEIM.
